DESIGN FOR A GOLF CLUB HEAD

Martin J. Flynn, Chicopee, Mass., assignor to A. G. Spalding & Bros. Inc., Chicopee, Mass., a corporation of Delaware

Application June 8, 1939, Serial No. 85,394

Term of patent 14 years

To all whom it may concern:

Be it known that I, Martin J. Flynn, a citizen of the United States, residing at Chicopee, in the county of Hampden and State of Massachusetts, have invented a new, original, and ornamental Design for Golf Club Heads, of which the following is a specification, reference being had to the accompanying drawing, forming a part thereof, and in which:

Fig. 1 is a side elevational view of a golf club head showing my new design; and

Fig. 2 is an end elevation thereof.

I claim:

The ornamental design for a golf club head, substantially as shown.

MARTIN J. FLYNN.
